UNITED STATES PATENT OFFICE.

LOUIS J. RIEGLER, OF BEN AVON, PENNSYLVANIA.

ANTICREEPER FOR RAILS.

1,170,105.

Specification of Letters Patent. Patented Feb. 1, 1916.

Application filed November 13, 1915. Serial No. 61,240.

To all whom it may concern:

Be it known that I, LOUIS J. RIEGLER, a citizen of the United States, and resident of Ben Avon, in the county of Allegheny and State of Pennsylvania, have invented a new and useful Improvement in Anticreepers for Rails; and I do hereby declare the following to be a full, clear, and exact description thereof.

10 My invention relates to anti-creepers for rails, such as devices for preventing the creeping of railroad rails along the ties, and such devices are also known as rail anchors and creep checks.

15 Anti-creepers as hereinbefore constructed, and used, are embraced in two general types, one of which is intended to grip the rail sufficiently to prevent creeping immediately upon being applied, and the other is intended that the creeping of the rail further tightens the grip and thus eventually prevents the creeping.

20 The object of my invention is to provide an anti-creep, which will have the advantages of both these types and to form a cheap, simple and efficient device of such character, which will be easy to manufacture, can be readily applied to the rails, and will maintain an effective grip upon the 25 rails in order to prevent the creeping of the same.

25 To these ends my invention consists, generally stated, in the novel arrangement, construction and combination of parts, as hereinafter more specifically set forth and described and particularly pointed out in the 30 claims.

35 To enable others skilled in the art to which my invention appertains to construct and use my improved anti-creep for rails, I will describe the same more fully, referring to the accompanying drawing, in which—

40 Figure 1 shows a cross section of the ordinary railroad rail having my improved anti-creep applied thereto and in position for clamping on such rail. Fig. 2 is a like view showing the wedge applied to the anti-creep for clamping the same to the rail. Fig. 3 is a side elevation of the wedge employed. Fig. 4 is an elevation of the rail 45 showing the anti-creep in position with respect to the rail and tie. Fig. 5 is a top view of the anti-creep. Fig. 6 is a view of the

filler block employed. Figs. 7 and 8 are 55 views of other forms of the anti-creep.

Like symbols of reference herein indicate like parts in each of the figures of the drawing.

As illustrated in the drawing A represents 60 the usual railroad rail having the head a, web b and bottom flange c. The yoke for fitting around the rail flange c is shown at 1 and is preferably formed in one piece and by rolling, casting or forging, so as to provide 65 for the body portion 2, and jaws 3 and 4 thereon. The jaw 3 is formed to fit closely over the edge of one side of the rail flange c and the jaw 4 is formed longer and with a greater opening between the same and the 70 body portion 2 so as to allow the jaw 3 to slip over its flange edge when the jaw 4 is moved up against the opposite flange. The central portion 5 of the body 2 of the yoke 1 is made thinner than at the ends of the same 75 where they are connected to the jaws 3 and 4, in order that it may bend freely at such portion when the yoke 1 is tightened on the rail flange c, as hereinafter described.

When the yoke 1 is being applied to the 80 rail flange c adjacent to the tie B supporting such rail A the jaw 4 is placed over one edge of said flange, and then the jaw 3 is placed in position over and against the opposite rail flange, so that while the yoke is being 85 held in this position, a filler block 6 formed by rolling, pressing or casting, is slid into place under the jaw 4 and against the rail flange, which will place the body portion 2 of such yoke in close proximity to the under 90 face of such flange. A wedge 7 formed by pressing or forging and having a tapered portion 8 and a depending portion or lug 9 is adapted to have its depending portion 95 placed against the tie B and its tapered portion inserted between the rail flange c and the central portion 5 on the yoke 1 by pressure applied to said yoke, so that when such wedge is forced into position said central portion will bend downward or outward, and the yoke and jaws 3 and 4 will tend to take the position as shown in Fig. 2, thereby enabling the said jaws to be drawn down on and tight against the outer edges and upper surfaces of the rail flange. 100 105

In Fig. 8 is shown another form of my improved anti-creep, in which the filler block 6 is dispensed with and a larger wedge

7 such as is shown, is used so that in this case the wedge is thick enough to bring the jaws 3' into contact with the rail flange c, both jaws being of the same length. This 5 form of the wedge has the pointed portion 7', and such form is adapted to increase the frictional contact area between the wedge and rail base and to transmit pressure to the yoke 1' only at the center, where it is most 10 effective. This principle may also be found effective for the form of wedge shown in Figs. 2, 3 and 4.

In Fig. 7, another form of the wedge 7' is shown in which the yoke engaging side of 15 the same is in the form of a segment of a circle, as at 7'', and the jaws 3' in this case are the same as those shown in Fig. 8, without 20 a filler block.

Various other modifications and changes 25 in the design and construction of my improved anti-creeper may be resorted to without departing from the spirit of the invention or sacrificing any of its advantages.

It will thus be seen that the yoke, as hereinbefore 30 described is designed to cause the body of the same to be stressed in direct tension, rather than in bending, when the wedge is forced in to cause the jaws of the yoke to grip the rail flanges. In one piece 35 yokes as heretofore constructed, the pressure developed by forcing in the wedge, causes bending stresses in the body of the yoke. The pressure therefore developed between the jaws of these former yokes and 40 the rail flanges, between the wedge and the bottom of the rail and between the wedge and yoke is limited to the strength of the body of the yoke acting as a beam, thus requiring a yoke made of a material having a 45 high elastic limit to develop sufficient pressure between the jaws and rail flanges for firmly gripping the rail. With the yoke of 50 my improved device the thin portion at the center allows the metal at such point to bend freely and act as a flexible connection, thus causing the jaws to draw inwardly toward the flanges of the rail, as the wedge is forced in and setting up tensile stresses only in the body of the yoke. The advantage of this is 55 obvious, as a given amount of metal offers considerably more resistance in direct tension than in bending.

In the one piece yokes heretofore constructed, the gripping pressure between the 55 jaws and the rail flanges is purely vertical, and such pressure sets up great bending stresses in the haunches of the jaws, and is due to the long lever arm of one of the jaws which is necessary to pass the jaws over the 60 rail flanges. In my improved anti-creeper, the pressure between the jaws and the rail flanges is horizontal and the lever arm is reduced, thus permitting greater pressure for gripping the rail flanges.

There is a further advantage in my improved anti-creeper, in that greater pressure can be developed to more firmly grip the rail flanges, than in the former constructions as in the latter, the pressure of the jaws on the rail flanges is equal to one-half that developed by the wedge when forced in, while in my improved construction it is equal to the pressure developed by the wedge when forced in, and multiplied a number of times, depending upon the ratio of the width of 75 the rail flange to the thickness of the wedge.

What I claim as my invention and desire to secure by Letters Patent is—

1. An anti-creeper for rails, comprising a yoke arranged substantially transversely of 80 the rail beneath its base, said yoke having a jaw at each end of the same for fitting around the rail flanges and a body portion provided with a thin central portion thereon adapted to bend freely, and a wedge adapted to be 85 forced between the bottom of the rail base and said central portion to bend said portion and cause the gripping of the rail flanges by said jaws.

2. An anti-creeper for rails, comprising 90 a clamping device arranged substantially beneath the rail base, said device having a body portion, a jaw at each end of the same for fitting around the rail flanges, one of 95 said jaws being enlarged and said body portion provided with a thin central portion, adapted to bend freely, a filler block fitting between the rail flange and the enlarged jaw, and a wedge adapted to be forced between the bottom of the rail base and said 100 central portion to bend said portion and cause the gripping of said rail flange and said filler block, respectively by said jaws.

3. An anti-creeper for rails, comprising a one piece yoke having a body portion fitting 105 under the rail base and a jaw at each end of the same for fitting around the flanges on said base, said body portion having a thin flexible portion intermediate of said jaws, and a wedge adapted to be forced between 110 the bottom of the rail base and said flexible portion to bend said portion and cause the gripping of the rail flange by said jaws.

4. An anti-creeper for rails, comprising a one piece yoke having a body portion fitting 115 under the rail base and a jaw at each end of the same for fitting around the rail flanges, one of said jaws being enlarged, said body portion having a thin flexible portion intermediate of said jaws, a filler 120 block fitting between the rail flange and the enlarged jaw and a wedge adapted to be forced between the bottom of the rail base and said flexible portion to bend said portion and cause the gripping of said rail 125 flange and said filler block, respectively by said jaws.

5. In a rail anchor, the combination with

a one piece yoke having jaws adapted to embrace the edges of the rail base, of means for distorting said yoke between said jaws, thereby to create tension therein and cause

5 said jaws to grip said rail base.

6. In a rail anchor, the combination with a one piece yoke having jaws adapted to embrace the edges of the rail base, of means for bending downwardly said yoke between

said jaws, thereby to create tension therein 10 and cause said jaws to grip said rail base.

In testimony whereof, I the said LOUIS J. RIEGLER, have hereunto set my hand.

LOUIS J. RIEGLER.
